UNITED STATES PATENT OFFICE.

ADAM PLEIN AND JOSEPH W. HOFFMANN, OF PEWAUKEE, WISCONSIN, ASSIGNEES OF ONE-FOURTH TO GEORGE CLOOS, OF MILWAUKEE, WISCONSIN.

TIME-CONTROL CUT-OUT SWITCH.

Application filed July 19, 1926. Serial No. 123,426.

This invention relates to time control cut-out switches.

Although the invention may be applied to a large number of uses it is particularly intended for use in connection with a radio receiving set.

In radio receiving sets, it is the usual custom to turn on the "A" battery and tune in the station. Thereafter, the operator usually leaves the set and attends to other work, allowing the set to operate without any attention on his part. It frequently happens that he forgets to shut the "A" battery off, even after the station has ceased sending. There is nothing to call his attention to the fact that the "A" battery is being used, and it frequently happens that the battery is completely depleted by this needless expenditure of energy.

This invention is designed to overcome the defects noted above, and objects of such invention are to provide a time control cutout switch, particularly adapted for use in connection with radio receiving apparatus, and so designed that the operator may readily set the switch to open at any desired time, and thus to cut out and save the "A" battery.

Further objects are to provide a simple and neat type of switch which may be combined with an ordinary alarm clock without detracting from the apparatus of the clock, and which may be readily connected with the radio receiving set and with a storage battery or other type of "A" battery.

An embodiment of the invention is shown in the accompanying drawings in which:

Figure 1 is a view of the apparatus as it appears when in operation;

Figure 2 is a side view of the switch and clock with which it is associated.

Referring to the drawings, it will be seen that a conventional type of radio receiving apparatus is provided, as indicated by the reference character 1, and that this receiving set is provided with binding posts or other terminals 2, adapted to be supplied from the "A" battery 3.

An ordinary type of alarm clock 4 is employed, and the alarm shaft or winding shaft 5 is preferably extended and provided with an operating arm 6. This shaft is also provided with an oval or other shaped cam 7 which operates between a pair of spring fingers 8. These spring fingers are carried by an insulating block 9, rigidly secured to the

back of the alarm clock. Further, it is to be noted that the cam 7 is provided with a pin 10 to limit its motion. This pin operates within a slot 11 formed in one of the spring arms 8, as most clearly shown in Figure 2. The spring fingers 8 are provided with a pair of contacts 12 which are adapted to close the "A" battery circuit when they are together.

A pair of conductors 13 and 14 extend from the contact fingers 8. One of these conductors leads to a binding post 2 and the other is preferably provided with a spring clamp 15 adapted to engage a terminal of the battery 3. A third conductor 16 extends from the other binding post 2, to the remaining terminal of the battery and is similarly provided with a contact clamp 15.

In using the apparatus, it is merely necessary to set the alarm at any desired point, such alarm being usually set by means of an adjusting knob 17. Thereafter, the operator locks the lever 6 to the left, as shown in Figure 1, and thus permits the spring fingers 8 to close the "A" battery circuit. Thereafter, the operator may leave the set with assurance that the battery will be cut off after the desired interval has elapsed.

It will be seen, therefore, that a novel combination has been provided, whereby the wasting of the battery for a radio receiving set is prevented. Further, it will be seen that the clock may serve at its usual capacity without detracting from its appearance or its customary mode of functioning.

It will be seen further, that one of the spring arms is so related to the cam that it will arrest the motion of the cam at the desired point.

Although the invention has been described in considerable detail, such description is intended as illustrative rather than limiting as the invention may be variously embodied and as the scope of such invention is to be determined as claimed.

I claim:

In a time control switch, the combination of an alarm clock provided with an alarm arbor, a cam carried by said arbor, an insulating member secured to the body portion of said clock, a pair of spring arms embracing said cam and carried by said insulating member and having contacts adapted to close an electric circuit, one of said spring arms having a slot formed there-

in having terminal portions, said arbor having a projecting member adapted to operate in said slot to thus limit the motion of said arbor, whereby said cam is stopped, when
5 the spring arms are separated, by the contacting of the projecting member with a terminal portion of the slot.

In testimony that we claim the foregoing we have hereunto set our hands at Pewaukee, in the county of Waukesha and State of ¹⁰ Wisconsin.

ADAM PLEIN.
JOSEPH W. HOFFMANN.
